United States Patent Office

Des. 189,097
Patented Oct. 25, 1960

189,097

GAME BOARD

Richard W. Pecina, 1907 Chippewa Road, and Ramon P. Georges, 1913 Chippewa Road, both of Waukegan, Ill.

Filed Mar. 18, 1960, Ser. No. 59,785

Term of patent 14 years

(Cl. D34—5)

FIG. 1.

FIG. 2.

The dominant features of our design reside in the portions shown in full lines.

We claim:

The ornamental design for a game board, as shown and described.
